DESIGN FOR A CONTAINER FOR CIGARETTES OR SIMILAR ARTICLES

Elmer G. Engel, Joseph F. Scott, and Gerard Victor Korda, New York, N. Y.

Application September 6, 1945, Serial No. 121,890

Term of patent 3½ years

(Cl. D85—7)

To all whom it may concern:

Be it known that we, Elmer G. Engel, a citizen of Hungary, Joseph F. Scott and Gerard Victor Korda, both citizens of Czechoslovakia, residing in the city, county, and State of New York, have invented a new, original, and ornamental Design for a Container for Cigarettes or Similar Articles, of which the following is a specification, reference being had to the accompanying drawing, forming a part thereof, in which:

Fig. 1 is a perspective view of a container for cigarettes or similar articles embodying our new design;

Fig. 2 is a top plan view thereof;
Fig. 3 is an end elevation thereof; and
Fig. 4 is an end elevation of the opposite end thereof.

We claim:

The ornamental design for a container for cigarettes or similar articles, as shown.

ELMER G. ENGEL.
